DESIGN FOR A SOAP BOX

Marjorie J. Thomasson, Mount Lebanon, Pa.

Application February 11, 1942, Serial No. 105,764

Term of patent 7 years

To all whom it may concern:

Be it known that I, Marjorie J. Thomasson, a citizen of the United States, residing at Mount Lebanon, in the county of Allegheny and State of Pennsylvania, have invented a new, original, and ornamental Design for Soap Boxes, of which the following is a specification, reference being had to the accompanying drawing, forming a part thereof.

I claim:

The ornamental design for a soap box, as shown.

MARJORIE J. THOMASSON.
